UNITED STATES PATENT OFFICE.

EUGENE NAPOLI, OF NEW YORK, N. Y.

CAP FOR CONTAINERS.

1,269,953.

Specification of Letters Patent. Patented June 18, 1918.

Application filed August 8, 1917. Serial No. 185,172.

To all whom it may concern:

Be it known that I, EUGENE NAPOLI, a subject of the King of Italy, residing at New York, in the county of New York and 5 State of New York, have invented new and useful Improvements in Caps for Containers, of which the following is a specification.

This invention relates to caps for containers or receptacles, the invention being 10 more particularly related to dispensing caps or tops for containers such as milk bottles, pitchers and the like, salt and pepper receptacles, toilet powder receptacles and the like.

The main object of the invention is the 15 provision of a dispensing cap or top which is adapted to close automatically against the entrance of foreign matter when the employing container or receptacle is placed in upright position, and which is also adapted 20 to open automatically when the employing receptacle is tilted or inclined in the customary manner, for the desired dispensing of the contents thereof.

Another object of the invention is to provide 25 a cap or top, the general structural elements of which are so arranged that the device may be manufactured separately and then removably applied to the container or receptacle, or that, on the other hand, it 30 may be built in or constructed with the container or receptacle itself.

With these and other objects in view, the 35 invention resides in the details of construction, and in the arrangement and combination of parts hereinafter described and shown in the accompanying drawings, forming a material part of this specification, and in which:—

Figure 1 is a view in side elevation of a 40 fragmental portion of a conventional milk bottle, showing my improved cap applied thereto.

Fig. 2 is a similar view, but showing the 45 bottle inclined at an angle with the movable portion of the cap swung into open position to permit delivery of the contents.

Fig. 3 is a top plan view of my cap detached.

Fig. 4 is a vertical sectional view through 50 the cap.

Fig. 5 is a similar view, but showing a modified form of the cap as employed for non-liquid contents.

Fig. 6 is a fragmental elevational view, illustrating my cap as constructed with a dispensing container.

Like characters of reference indicate like parts throughout the accompanying drawings.

With more particular reference to the accompanying drawings, the numeral 10 denotes the cup-like body portion of the cap, the same terminating at its upper end in an outwardly flaring flange 11, which in the present embodiment of my invention is curved downwardly in order to engage snugly upon the thickened curved rim or bead 12 of a milk bottle as 13. The integral partial bottom section 14 of this cup-like body 10, being preferably inclined at an angle, extends upwardly for a distance beyond the flange 11 to form the rear inclosing wall 15 of the dispensing spout. The front wall 16 or complementary portion of this spout rises from the inner side or periphery of the body portion 10 directly opposite the rear wall 15, both walls being integrally united liquid-tight just below the flange 11, and then separating again after a short distance and flaring in opposite directions as at 17 to complete the dispensing spout. A channel 18 communicating with the interior of the milk bottle or receptacle, is thus formed, through which to dispense the contents.

Secured to the top of the body portion 10 directly opposite the spout thus formed, is a sector-like plate 19, portions of the straight marginal edge of which are curved upon themselves to provide hinged knuckles or bearings as 20. Hinged for swinging movement upon a pin or longitudinal axis 21, arranged in the bearings 20, is a cover plate 22 of sufficient size to engage the top periphery of flange 11, thereby, in connection with the sector-like plate 19, completely inclosing the top, the said cover plate 22 being outwardly deformed in such manner as to provide an inner space or cavity 23 of such size as to clear the projecting spout 17.

Integrally united with the cover plate 22 at the hinge or axis 21 is an arm 24, which projects therefrom at an angle, preferably at a little less than a right-angle, and to which is secured a weight 25, considerably heavier than the said cover plate 22; and it

will be noted in this connection that the weight thus supported is adapted to swing freely across the opening or cavity formed between the curved wall 14 and the inner periphery of the body 10. Thus swung upon the horizontal axis 21, the cover plate 22 and the weighted arm 24 move together in angular relation to each other, it being manifest that since the weight 25 overbalances the weight of the cover plate 22, the said weight will always maintain the cover plate in close engagement with the top periphery of the flange 11, when the body portion 10 is held in horizontal position, and also that the said weighted arm 24, in obedience to the law of gravity, will force the cover plate 22 away from the dispensing spout 17, whenever the body 10 is inclined at an angle. Thus, in Fig. 1, showing the receptacle in upright position, it will be seen that the weighted arm holds the cover plate in engagement with the body flange completely inclosing the spout; while in Fig. 2, showing the receptacle inclined at an angle, the weighted arm is seen holding the cover plate above the spout so that the contents of the receptacle may be dispensed.

In order to removably secure my cap liquid-tight to the neck of the container, I employ preferably around the body 10, below the flange 11, a ring or layer of cork as 26, or other suitable material.

In the modification shown in Fig. 5, the spout 17 is replaced or substituted by the closed wall 27, which is provided with a plurality of apertures as 28, through which the contents of the receptacle may be dispensed. This form of cap or cover is used preferably for receptacles designed to contain powdered or granular substances, such as pepper, salt, toilet powder and the like. Instead of making the cap as a separate closure, adapted to be removably engaged with the container, it may be constructed with the container itself as a permanent feature thereof. This is preferably accomplished by making the neck of the container in the form of the cup-like body 10, all other parts being precisely the same, although it will be manifest that good results may also be attained by permanently securing the cup-like body, when made separately, within the neck of the container by soldering or any suitable well-known means.

Having thus described my invention, what I claim is:

1. A dispensing cap for containers including a cup-like body portion formed with a top rim or flange, and formed further with part of its integral bottom wall upturned to form in conjunction with the adjacent interior periphery of the cup-like body the rear section of a wall extending upwardly above said rim to form part of a dispensing

spout, a complementary section rising from 65 within the said rim and united with said upwardly extending wall to complete the dispensing spout, a cover plate hingedly supported upon said rim opposite said spout, said cover plate being deformed to compensate for the projecting portion of the spout, and a weighted arm integrally united with said cover plate at an angle, said weighted arm being adapted to operate in the cup-like cavity behind said spout and being 75 heavier than said cover plate to swing the same into closed or open position upon the rim accordingly as the cup-like body occupies a horizontal or inclined position.

2. A dispensing cap for containers, comprising a cup-like body adapted to fit in the neck of a container and formed with a top rim or flange portion adapted to overlie the top end of the container, a dispensing spout rising from the bottom of said body within 85 the periphery of said rim and projecting thereabove, a sector plate secured upon said rim opposite said spout, a cover plate hinged to said rim, said cover plate being deformed to compensate for the projecting spout, and 90 a weighted arm integrally united with said cover plate at an angle, said weighted arm being adapted to swing across the cavity behind said spout and being heavier than said cover plate to swing the same into 95 closed or open position upon the rim accordingly as the cup-like body occupies a horizontal or inclined position.

3. In combination with a container having a neck portion flared to form a rim, a wall 100 extending partially across said neck portion below said rim and projecting upwardly therein dividing the neck portion into a cavity and a dispensing channel, said wall extending above the rim to provide a section 105 of a delivery spout, a second section rising from within said rim and united to said first wall to complete the delivery spout, a cover plate hingedly supported upon said rim opposite said spout, said cover plate being deformed to compensate for the projecting spout, and a weighted arm integrally united with said cover plate at an angle, said weighted arm being adapted to swing across 110 said cavity and being heavier than said cover 115 plate to swing the same into closed or open position accordingly as the container occupies a horizontal or inclined position.

4. The combination of a cup-like body formed with a top rim and with its bottom 120 wall extending upwardly therein dividing the interior of the cup-like body into a cavity portion and a spout portion, said wall continuing upwardly for a distance above said rim to form a section of a spout, a second wall rising from within said rim and united to said spout section to complete the dispensing spout, a cover plate hingedly 125

supported upon said rim opposite said spout, said cover plate being deformed to compensate for the projecting portion of said spout, and a weighted arm integrally united 5 with said cover plate at an angle, said weighted arm being adapted to swing across said cavity and being heavier than said cover

plate to swing the same into closed or open position upon the rim accordingly as the cup-like body occupies a horizontal or inclined position. 10

In testimony whereof I have signed my name to this specification.

EUGENE NAPOLI.
